DESIGN FOR A TEXTILE FABRIC

Attilio Gatti, New York, N. Y.

Application January 21, 1937, Serial No. 67,204

Term of patent 3½ years

To all whom it may concern:

Be it known that I, Attilio Gatti, a citizen of Italy, residing at 66 Park Avenue, New York, in the county of New York and State of New York, have invented a new, original, and ornamental Design for a Textile Fabric, of which the following is a specification, reference being had to the accompanying drawing, constituting a part thereof.

The fabric is a plan view of a piece of the textile fabric showing my new design.

I claim:

The ornamental design for a textile fabric substantially as shown.

ATTILIO GATTI.
